UNITED STATES PATENT OFFICE.

CHARLES J. NOVAK, OF CEDAR RAPIDS, IOWA.

SAW-FRAME STRETCHER.

SPECIFICATION forming part of Letters Patent No. 732,315, dated June 30, 1903.

Application filed January 13, 1903. Serial No. 138,941. (No model.)

To all whom it may concern:

Be it known that I, CHARLES J. NOVAK, a citizen of the United States, residing at Cedar Rapids, in the county of Linn and State of Iowa, have invented certain new and useful Improvements in Saw-Frame Stretchers, of which the following is a specification.

The object of this invention is to provide a bucksaw-frame with a stretcher adapted for the quick and easy straining and releasing of the saw, so that when not in use the saw-frame may be relieved of the tension necessary when it is in use.

The nature of the invention will clearly appear from the description and claim following, reference being had to the accompanying drawing, which is a side view, partly in section, of a saw-frame with my improved stretcher attached.

The saw-frame A does not differ essentially from those in common use, except that near the upper end of the handle-bar A' is attached a toothed plate J by screws K. This plate is adapted to engage the teeth I of a cam-lever H, pivoted to one looped end of the stretcher-tie B. The stretcher-tie is composed of a single piece of wire twisted in the middle portion to the desired tension when strained by the cam-lever. One loop D embraces the upper end of the handle-bar and passes through an eye in the cam-lever. Thence it returns and is twisted in a coil G, which embraces the other end portion back of a few turns of coil F. Thence this part of the wire branches laterally at E, and then turns outwardly in a part which passes into a hole L in the handle-bar A'. As shown, the stretcher is in the straining position. In this position of the

cam-lever the straining-line passes slightly below the point of engagement of the cam 40 with the toothed plate, and the cam is thus held firmly in position, with the end of the handle in contact with the handle-bar. It is instantly released by a pull of the finger. The extension E serves as a spring to prevent the 45 parts from flying out of proper position and engagement when the cam-lever is released.

The device, as will be seen, admits of the saw being strained or relaxed in a moment. Instead, therefore, of leaving the saw strained 50 when not in use, as is usual when considerable time must be taken to screw up a thumb-nut or the like, the operator simply touches the cam-lever when through sawing and the frame is instantly relieved of the strain, which 55 if continuous buckles and twists it quite out of shape.

Having thus described my invention, what I claim as new, and desire to secure by Letters Patent, is—

In combination with a bucksaw-frame, a stretcher, comprising a toothed plate adapted for attachment to the saw-frame handle-bar, a toothed cam-lever to engage therewith, and a stretcher-tie composed of a single piece of 65 wire, looped at each end, one loop passing through an eye in the cam-lever, and having a downwardly and backwardly extending elastic member entering a hole in the saw-frame, substantially as and for the purpose set forth. 70

In testimony whereof I affix my signature in presence of two witnesses.

CHARLES J. NOVAK.
